CHAIN MOUNTING FOR REFLECTOR
BUTTONS

William H. Scaright, Toledo, Ohio, assignor, by
means assignments, to Western Cataphoto
Corporation, Toledo, Ohio, a corporation of
Ohio

Application August 26, 1934, Serial No. 740,591

7 Claims. (Cl. 40—130)

This invention is directed to new and useful improvements in mountings for autocollimators or reflector buttons used in forming reflecting signs.

5 Its primary object is to provide a plurality of casings adapted to house such reflector buttons pivotally joined together at their bases by means of laterally extending ears to form a flexible chain whereby characters of any desired shape 10 can be formed and secured to a panel.

A further object is to provide such ears with apertures through which they may be secured in position on a panel.

15 Still a further object is to provide relatively fragile members for holding the mountings together through the ears whereby the chain may be manually severed at any desired point as is necessitated in forming characters which make up the sign.

20 Another object is to provide such a chain of mountings which will maintain the reflector buttons in uniform spaced relationship.

25 Still another object is to provide a series of connected reflector button housings which will greatly facilitate the forming of reflector signs either in the field or at the factory without necessitating any prior preparation of the sign panels.

Another object is to provide such housings for the buttons which will securely hold the buttons 30 in operative position after attachment to the sign panel.

A further object is to provide mountings of simple and inexpensive construction.

Other objects and advantages will be apparent 35 from an examination of the following detailed description of this invention.

In the drawing:

Fig. 1 is a front elevation of a reflector sign formed by a plurality of chains of the mountings 40 embodying this invention.

Fig. 2 is a plan view of a chain of four mountings with reflectors.

Fig. 3 is a side elevation of the structure shown in Fig. 2 partly in section.

45 Fig. 4 is a perspective view of three mountings without buttons, one being in section.

Fig. 5 is a perspective view of an alternative type of rivet for securing the housing together.

In detail the individual mountings or housings 50 1 for the reflector buttons are stamped in the form of a tapered hollow cylinder open at both ends with the upper edge turned in to form a shoulder 2 the edge of which describes a circle of sufficient diameter to permit the object lens 55 of the reflector button to extend therethrough.

Extending laterally at opposite sides of the base of the housing 1 are ears 3 provided with apertures 4. One of these ears on each of these housings is offset from its opposite ear so as to be on a slightly higher horizontal plane for the 5 purpose hereinafter described. A plurality of such housings are pivotally joined together by means of relatively fragile hollow rivets 5 positioned through the apertures 4 of the ears 3. In securing them together in this manner each offset ear is positioned over a non-offset ear on an adjacent device. Thus the level of the assembled chain is maintained.

The glass reflector buttons 6 are of tapered cylindrical shape each having an object lens 7 and a reflecting portion 8 and provided with a shoulder 9 adapted to coact with the shoulder 2 of the housing 1 to hold the button from excess forward movement through the housing. A metal cap 10 fits around the rear portion of the glass 15 button 6. The shoulders 9 and 2 prevent forward motion of the button, the cap 10 assures a snug fit against the walls of the housing and the housing is so dimensioned that it will permit the rear of the cap 10 to extend rearwardly slightly so 20 that when the housing is secured to a panel the panel will press against the cap and hold it 25 securely in position.

An alternative or supplemental means for holding the button in position is indicated in Fig. 5 30 in which a rivet 11 is provided with an extension 12 adapted to be positioned across a part of the rear of the housing as shown in Fig. 3.

It is obvious that by means of this chain construction any characters can be formed for example as shown in Fig. 1 without preparing the panel for the reception of the units. By examination of the word "Stop" formed on the panel in Fig. 1 it will be seen that characters S, O and P are each formed by a continuous 35 chain of the units and that the letter T is formed from two shorter chains. The chains can be secured in the desired positions by means of nails or screws through the apertures 4 at any point. After a character is preliminarily formed the 40 chain may be manually severed to do away with any excess units and also the units can be simply joined together, if greater length of chain is 45 needed by manual riveting.

By use of this invention any desired combination of characters can be quickly, simply, and inexpensively formed on a panel to construct an attractive sign clearly legible in day and night.

I claim:

1. A mounting for reflector buttons compris-

55

ing a plurality of housings, laterally extending ears on each housing formed with apertures and hollow means extending through said apertures pivotally joining said housings and adapted to receive means for securing said joined housings to a panel.

2. A mounting for reflector buttons comprising a plurality of housings, laterally extending oppositely disposed offset ears on each housing and hollow rivets extending through said ears joining said housings together to form a separable chain.

3. A mounting for reflector buttons comprising a plurality of housings each housing comprising a hollow tapered cylinder open at both ends, the edge of the smaller end turned inwardly to form a shoulder, oppositely disposed laterally extending ears formed at the larger end and means extending through the ears of adjacent housings pivotally joining said housings to form a flexible chain of housings.

4. A panel mounting for reflector buttons comprising a plurality of housings adapted to partially encase such buttons, each housing comprising a hollow shell open at both ends, oppositely disposed laterally extending offset ears at one end provided with apertures, means extending through the apertures of complementary ears of adjacent housings to removably and pivotally join the housings together to form a flexible chain of housings, said ears adapted for receiving means for securing said chain to a panel.

5. A reflector sign comprising a panel, a plurality of reflector button housings, reflector buttons in said housings, oppositely disposed laterally extending ears formed with apertures on each housing, hollow members positioned through said ear portions joining some of said housings, characters formed by said joined housings and means positioned through said hollow members for securing said housings to the panel.

6. A mounting for reflector buttons comprising a plurality of housings provided with open ends through which they receive reflector buttons, reflector buttons in said housings, a pair of oppositely disposed ears on each housing and means joining said housings together through said ears each such means provided with an extension portion positioned in a direction across the said open end of a housing to retain the button in the housing.

7. A mounting for reflector buttons comprising a plurality of housings provided with open ends through which they receive reflector buttons, reflector buttons in said housings, a pair of oppositely disposed ears on each housing and means joining said housings together through said ears comprising a plurality of rivets each with an extending arm positioned in a direction across the said open end of a housing to retain the button in the housing.

WILLIAM H. SEARIGHT. 30
